FIG. 1

FIG. 2

FIG. 3

FIG. 4

FIG. 5

FIG. 1 is a top plan view of a drinking glass showing my new design;

FIG. 2 is a side elevational view thereof;

FIG. 3 is a bottom view thereof;

FIG. 4 is a sectional view thereof taken substantially along the section line 4—4 of FIG. 1; and

FIG. 5 is a perspective and partially broken away view thereof.

The characteristic feature of my design for a drinking glass is the interior configuration of the drinking glass as shown in FIGS. 1, 4, and 5.

I claim:

The ornamental design for a drinking glass, as shown and described.
